UNITED STATES PATENT OFFICE.

AUGUST FRITSCH, OF ENGELFELD, SASKATCHEWAN, CANADA.

COMBINED BRUSH-CUTTING AND ROAD-SCRAPING MACHINE.

Application filed March 27, 1924. Serial No. 702,309.

My present invention appertains generally to improvements in the art of brush cutting and road scraping machines, as described in the present specification illustrated in the accompanying drawings forming a part of the same.

The invention consists essentially of the novel features pointed out broadly and specifically in the claim for novelty following 10 a description containing an explanation in detail of an acceptable form of the invention.

The present invention is characterized by the provision of a vertically adjustable frame carrying a moldboard to which brush cutting knives may be attached, so that the machine may be used, for instance, to cut brush or other obnoxious growth along the sides of a road, after which the ground disturbed or torn up by the cutting of the brush 20 may be graded by the same machine upon removal of said brush cutting knives.

With the foregoing in view, the invention has for a further object the provision of a machine of this character having a 25 frame structure adjustably supported upon ground wheels so that the moldboard and brush cutting knives carried thereby may be vertically adjusted with respect to the surface of the ground traversed without 30 changing the parallel relation of the same.

In addition, the invention has for a further object the provision of machines for raising and lowering the forward or rear portions of the machine as required.

The invention has for a further object, 35 the provision of a combined brush cutting and road scraping machine in which the blades may be readily attached or detached and the draft attaching means reversed when 40 converting the machine from the brush cutting machine into the road scraping machine or vice versa.

With the foregoing and other objects in view, as will appear as the description proceeds, the invention consists in the novel construction, combination and arrangement of co-operating elements, as hereinafter more specifically set forth, claimed and shown in the accompanying drawings forming a part 50 of the present application, in which:

Fig. 1 is a plan view of the machine assembled as the brush cutting machine.

Fig. 2 is a side elevation of the machine as shown in Fig. 1.

Fig. 3 is a detail section, substantially on

the plane of line 3—3 of Fig. 2, looking in the direction indicated by the arrows.

Fig. 4 is a detail section, substantially on the plane of line 4—4 of Fig. 3, looking in the direction indicated by the arrows.

Fig. 5 is a detail perspective of the blade to be substituted when the machine is assembled as a road scraping machine.

Referring more in detail to the drawings in which similar reference characters designate corresponding parts throughout the several views, it is to be noted that the machine includes a main frame composed of the longitudinal side frame member 10, a forward angular side frame member 11 and a rear angular side frame member 12. This last mentioned side frame member 12 has a portion 13 bent to form a rear frame member connected with the rear end of the longitudinal side frame member 10 by a corner connecting member 14 or other suitable means. The angular side frame members 11 and 12 are connected at their respective rear and forward ends by a connecting plate 15 having angular edges 16 or by other suitable means. The transverse frame member 17 has one end secured on the plate 15 while its other end is secured between brackets 18 connecting the same with the longitudinal side frame member 10, as shown clearly in Fig. 1. It will also be seen from Fig. 1 that the forward end of the angular side frame member 11 is connected with the forward end of the longitudinal side frame member 10 by a connecting bracket 19 or other appropriate means. The transverse platform 20 is extended across the frame structure and an appropriate driver's seat 21 is mounted thereon. The transverse rear axle 22 is suspended in suitable bearing brackets 23 suspended in the rear end of the frame structure and has ground wheels 24 mounted thereon. An adjusting lever 25 is employed for adjusting the height of the axle 22 by raising and lowering the same with respect to the main frame. A link connection 26 is formed between the lever 25 and the axle 22 and the lever 25 may be readily locked in adjusted position on the segmental rack 27, which latter is supported in a suitable manner on the platform 20, while the lever 25 is pivotally mounted on

the auxiliary frame member 28. It is also to be seen from Fig. 1 that the bearing brackets 23 are suspended on a transverse supporting rod 29 extended through the rear portion of 5 the main frame and forwardly of the rear axle 22.

A pair of parallel diagonally extended frame members 30 are provided in the forward portion of the main frame with their 10 rear ends secured to the transverse frame member 17 while their forward ends connect with the forward diagonal side frame member 11. The axle 31 is extended across the auxiliary frame members 30 and carries 15 the traction wheel 32 having the angular plates 33 provided on its periphery and extending diagonally across the same at a different angle from the angle at which the traction wheel 32 is positioned in the main 20 frame. Pinions 34 are carried on the opposite ends of the axle 31 and work on racks 35 in substantially inverted U shaped bearing brackets 36 carried on the auxiliary frame members 30, for the axle 31. A worm 25 wheel 37 is carried on the axle 31 and driven by the driving worm 38 meshing therewith and carried on the forward end of the adjusting rod 39. A suitable bracket 40 is mounted on the axle 31 to support the 30 forward end of the adjusting rod 39. It will be seen from Figs. 1 and 2 that the adjusting rod 39 extends through the guide bracket 41 pivoted to the upstanding supporting member 42 carried on the trans- 35 verse frame member 17 and the hand wheel 43 is provided on the rear end of the adjusting rod 39 within ready reach of the operator, for operating the adjusting rod 39 to raise or lower the axle 31 and thereby 40 regulate the height of the main frame with respect to the surface over which the machine is operating.

The series of standards 44 are mounted on the forward angularly extended frame member 11 and braced by inclined bracing members 44^a connected therewith at their 45 upper ends while their lower ends are mounted on the longitudinal side frame member 10, the transverse frame member 50 17 and one of the angular frame members 30. The rail 45 is mounted on the upper ends of the standards 44. This structure may be seen in Figs. 1 and 2 and it is apparent that the standards 44 and rail 45 55 will protect the traction wheel 32 from the brush cut by the machine during operation of the same as the brush cutter. The rail 45 may be constructed of angle iron, as shown in Fig. 2, or in any other manner 60 desired.

The series of staggered cutting blades 46 are secured on the outturned lower edge 47 of the scraper 48 mounted on the outer face 65 of the angularly extended forward frame member 11, as shown clearly in Figs. 1 and 2.

The cutting edges of the blades 46 are slightly offset from one another and in substantially parallel planes with the cutting edges of the blades positioned in advance of one another toward the forward end of the machine, so that each blade will follow the one forwardly thereof in its cutting action on the brush, as the machine advances, thereby giving a series of glancing or diagonal cuts to the brush during operation of 75 the machines. This may be clearer understood as the description proceeds.

The draft means for the machine includes a clevice 49 carried on the forward ends of the draft bars 50, which have their forward ends parallel and secured together, while their main portions diverge after being extended in substantially parallel relation, the extreme rear ends 51 being again turned and extended rearwardly and also slotted. The 80 attaching members 52 are extended through the rear ends of the draft bars 50 to secure them to the longitudinal side frame member 10 and one of the auxiliary frame members 30, as shown clearly in Fig. 1. It will be seen from this view that the main portions of the draft bars 50 are extended outwardly across the longitudinal frame member 10 before being extended forwardly in parallel relation and connected, thus supporting the clevice 49 outwardly of the longitudinal side frame member 10, as well as slightly forwardly of the same. A brace bar 53 is connected by one end to the connected forward ends of the draft bars 50 85 while its other end is attached to the forward end portion of the longitudinal end frame member 10, thereby bracing and assisting in supporting the draft bars 50 in 90 proper position. A pointed guide blade 54 is adjustably mounted in the clamping bracket 55 on the longitudinal frame member 10, near the forward end of the latter and in depending position, so as to serve to guide 95 the machine in a straight forward direction and prevent the same from swaying from side to side while cutting the brush.

This operation of the machine as a brush cutter will be apparent from the foregoing 110 paragraphs taken in connection with the accompanying drawings without further detail description. Attention may be directed, however, to the position of the cutting blades 46 and the mounting thereof 115 with relation to the draft means and the angularly positioned traction wheel 32 and rear axle 22, as the relative position and arrangement of these parts assure efficient 120 operation of the cutting blades 46 on the brush at all times during operation of the machine. The construction of the main frame and the mounting of the operative parts on the same also assure efficient operation of the machine as a brush cutter with 125 the minimum strain on the different parts. 130

It is apparent from the foregoing disclosure that the invention is particularly adapted for road work, to first cut brush from along the sides of the road and subsequently grade along the sides of the road where the soil has been distorted and turned up as a result of the brush cutting operation.

For road scraping or grading purposes, such as premised, the centre of draft should be in front of the scraper 48. This is made possible by disconnecting the draft rigging 50 from the main frame and reversing the same, as indicated in dotted position in Fig. 1.

15 What I claim as new is:

In a machine of the class described, comprising in combination a frame structure; said frame structure being formed with one portion in alignment with the direction of travel, a second portion having its forward end connected to and being disposed at an acute angle relative to said first portion and a third portion connecting the rear ends of

the first said portion and the second said portion; an auxiliary frame supported intermediate the said frame structure; a main supporting wheel mounted in said auxiliary frame and acting as a fulcrum relative to said structure; a means for raising and lowering of said auxiliary frame and said frame structure relative to said main supporting wheel; a mould-board carried by said second portion of said frame structure; a transverse supporting rod carried between the first and third said portions of said frame structure; brackets each having one end pivotally mounted on said rod and extending rearwardly therefrom; an axle supported in the other ends of said brackets; ground wheels mounted on said axle and a means for fixedly adjusting said wheels for tilting said frame structure relative to said main supporting wheel.

In testimony whereof, I affix my signature.

AUGUST FRITSCH.
